VARIABLE COUNTER CIRCUIT

Rudolph A. Cola, Camden, N. J., assignor to Burroughs Corporation, Detroit, Mich., a corporation of Michigan

Application February 29, 1956, Serial No. 568,459

9 Claims. (Cl. 315—8.5)

This invention relates to counter circuits and more particularly concerns a magnetron beam switching tube and circuit for providing a counter capable of increased speed of operation, of variable counting, and of bi-directional counting.

Devices of this general type have heretofore required elaborate control apparatus for regulating their operation. In most prior hard tube variable counters which operate with as high a vacuum as is practical to produce, the interconnections have utilized capacitive or inductive coupling devices, either alone or together, which cause serious time delays. Some devices of this character utilizing an electron beam have achieved improvements in speed of operation but require extensive and complex circuits for cleaning the beam from one position and resetting it at another position.

An important object of this invention is to provide an improved method for obtaining a variable count by simultaneously clearing an electron beam from one position and resetting emitted electrons into a beam on another position whenever the first position is reached in a counting sequence.

Another important object of this invention is to provide a variable counter circuit wherein one position of a beam switching tube is rendered unstable and drives another position into beam forming condition during the period when the beam dwells unstably on the one position and before the beam in that one position is cleared therefrom.

Another important object of this invention is to provide an adjustable variable counter wherein any position of a beam switching tube is adjustable to provide unstable beam-holding conditions and to drive any other particular position of the tube into beam forming conditions during the transient dwell of the beam on the unstable position.

Still another important object of this invention is to provide an improved bi-directional variable counter.

Various other objects, advantages and meritorious features of the invention will become more fully apparent from the following specification, appended claims and accompanying drawings wherein:

Fig. 1 is a schematic view of a magnetron beam switching tube;

Fig. 2 is a current and voltage plot of spade electrode characteristics;

Fig. 3 is a schematic diagram of a magnetron beam switching tube and associated counter circuitry;

Fig. 4 is a voltage-time plot of potentials on electrodes of a magnetron beam switching tube;

Fig. 5 is a schematic diagram of an adjustment circuit for a variable counter; and

Fig. 6 is a schematic diagram of a bi-directional counter.

As shown in Fig. 1, the magnetron beam switching tube 30 is a multiposition beam tube of the type shown and described in U. S. Patent No. 2,721,955 to Sin-pih Fan et al. This tube 30 comprises an evacuated and sealed envelope, an elongated cylindrical cathode 32 around which are disposed coaxial and concentric arrays of elec-

trodes. The array nearest the cathode comprises a plurality of trough shaped elements 33 with their convex surfaces facing the cathode 32. Elements 33 are commonly known as spades. Surrounding the first array is a second array of collector electrodes 34, commonly called targets. Each target 34 has a portion thereof aligned to cover the space between adjacent spades 33 and a short extension at one edge of this aligned portion which extension extends toward the concave surface of a spade. A third array of switching electrodes or grids 35 is positioned between the spades and the targets. Each grid 35 is aligned with an extending side portion of a spade 33 and near to the edge of target 34 which is opposite to the short extension of the target.

15 A magnetic field represented by the head-on view of arrow head H permeates tube 30, with its flux flowing substantially parallel to the cathode and toward the observer of Fig. 1. The strength of field H is adjusted to about two or three times the magnetron cut-off value, for about +100 volts on the spades 33 relative to cathode 32. If one of spades 33 is lowered to less than half the supply voltage, the electrons circling cathode 32 will form a beam which grazes one side of that spade and impinges upon the adjacent target 34. Once the beam is formed, a small portion of the beam falls upon the spade and produces an IR voltage drop in the series resistor 36 connected to each of the spade electrodes and produces the IR drop which holds the beam stably in that position.

However, a negative voltage applied to the grid 35, 30 which is nearest the target 34 which is taking the beam current, causes the beam to fan out toward that grid 35 until it strikes the next spade 33 as well. This current produces a voltage drop in this next spade which causes the beam to switch to the next target. This switching can be continued by lowering the potential of the grid 35 which is in the same interspade space as is the beam, drawing the beam over to the next spade and thence to the next target. Similar voltage variation on grids other than the one near the electron beam do not cause this switching 40 until the beam is in the same inter-spade space. The beam switches from one target to the next within a small fraction of a microsecond of when the grid reaches switching potential, and remains on this next target in a stable condition until the next grid is lowered to switching potential. With a proper sequence of switching potentials on sequential grids 35, the electron beam advances clockwise around tube 30, energizing each target 34 in succession.

50 When the tube 30 is turned on, magnetic field H will keep the tube's beam cut off, since the field H exceeds the field needed for magnetron type cut-off, with supply voltage +E applied. However, one of spades 33 can be lowered from +E to ground potential by closing switch 37. This change upsets the voltage gradients in the tube

55 and electrons form a beam which grazes the spade 33 which has a lowered potential and strikes the target 34 adjacent to the spade in the clockwise direction. As soon as part of the beam current flows to this spade, the resulting IR voltage drop in resistor 36 will hold the spade's 60 voltage down and keep the beam stably in position after switch 37 is opened.

The beam switching action of grids 35 can be provided in at least two ways. With alternate grids in common connections, to provide two such circuits of alternate 65 grids, an alternating voltage f_s can be applied on a center tapped or balanced circuit between these connections to switch the beam one position every half cycle. When one set of grids is driven negative so far as to cause switching, the other set of grids is driven to an equal and opposite positive voltage. This positive voltage on each "next grid" following each negative-driven grid will prevent switching

more than one position on each half cycle. On the following half cycle, the next switching-step occurs because voltage polarities reverse every half cycle. In place of a push-pull drive to the switching grids 35, all grids can be in one common connection 38 and driven by negative going pulses 39 which are controlled to be of switching level for only long enough for a single switching step to occur, after which the grids are brought back to a bias voltage to leave the beam stably in position until the next pulse 39 is applied.

Resistors 106 must have a load line which must be below the load lines for both R_M and R_m , as shown for R_s on Fig. 2, in order to hold the beam stably. Characteristic curve 40 is for a spade when the beam is switching over to that spade, from a previous counter clockwise position, and exists only so long as the preceding spade remains at its depressed potential. The spade which has been holding the beam is called the j spade, and the spade to which the beam is switching is called the $j+1$ spade. Accordingly curve 40 is called the $j+1$ characteristic and curve 41 is called the j characteristic. This curve 40 is not a stable beam position, but collapses to curve 41 as the potential of the preceding spade rises due to loss of its portion of the beam current, and as the beam strikes the next target and grazes the next or $j+1$ spade. Accordingly, any value of spade resistor 106 lower in ohmic value than R_M will present a sloped line on Fig. 2 with a slope which is greater than that for

$$\frac{1}{R_M}$$

and will not cause enough IR drop on the associated spade to hold the beam stably. A value of resistance between R_m and R_M will hold the beam only momentarily until the preceding or $j+1$ spade's characteristic collapses from 40 to 41, as the beam switches. Resistance values lower than R_m are wholly unsuitable for spade resistors.

Fig. 3 shows a variable counter circuit which utilizes the above described spade characteristics. The magnetron beam switching tube 30 of this circuit has its electrodes displaced linearly in a line but may be coaxially arranged as in Fig. 1. Switches 45 and 46 are provided to change connections for various beam positions and thus to vary the count for tube 30. Switch 45 reconnects target 34 from load resistor R_T to the lead connecting to the junction of resistors R_1 and R_2 . Switch 46 shunts spade resistor R_s with additional resistor R'_s . As shown, the switches are actuated for a count of three. Target T_3 (which is three targets from T_0) is connected by switch 45 back to the junction of R'_1 and R_2 , and spade S_3 is connected by switch 46 to a resistance R'_s , placing it in parallel with R_{s3} to give a resistance which is too low in ohmic value to hold the beam stably once the preceding spade returns to supply voltage V_s . Switching grids 35 are connected to a balanced circuit with bias $+V$, from center tap to ground. The beam is initially held by spade S_0 , striking target T_0 . As the beam is advanced by voltages on switching grids 35, it reaches spade S_3 and target T_3 . Target current flowing through R_1 lowers the voltage on spade S_0 , and the low resistance of resistors R'_s and R_{s3} in parallel prevents spade S_3 from attaining a low enough voltage to hold the beam in a stable manner, after the preceding spade returns to V_s . The voltage which spade S_3 does attain is enough to hold the beam only so long as the preceding spade is at the $j+1$ characteristic. Under these conditions, the beam clears from target T_3 and resets on target T_0 as soon as this $j+1$ characteristic collapses. A count out pulse is provided from target T_0 for every series of a selected number of pulses. In the example given this is three pulses. By proper selection of the spade-target position which is connected, as spade S_3 and target T_3 are connected in Fig. 3, any count up to the total number of positions in tube 30 can be obtained.

When the count equals the total number of positions, no cut-off-reset connections are used. The normal cycle of beam switching brings the beam around to the reset position. This is a count for which no variable counter circuit is needed, but all lower counts require a circuit for clearing and resetting as above described.

Fig. 4 shows the voltage variations which occur on spades S_3 and S_0 for the connections shown in Fig. 3. When no electron current strikes these spades, their potential is V_s . When the beam is switched to where a small portion strikes spade S_3 , this spade drops in potential by the amount of the IR drop through parallel spade resistors R_{s3} and R'_s having a resistance R''_s , i. e., $I_s \times R''_s$. The beam is held on this position for only a short interval of time. As soon as the preceding spade returns to voltage V_s , this IR drop is not enough to hold the beam, and the beam cuts-off allowing the spade S_3 to rise in potential at a rate determined by its RC constant, $R''_s \times C_s$, where C_s is the spade's capacity to other electrodes and to ground. However, while the beam is on spade S_3 and target T_3 , the larger target current flows through R_1 and produces an IR voltage drop $I_T \times R_1$ on spade S_0 which is a larger IR drop than that on S_3 . When the beam on target T_3 cuts off, spade S_0 begins to rise in potential; but a new beam forms on spade S_0 before its potential can rise beyond beam-forming level. Since the total value of R_1 plus R_2 is a resistance which provides for stable beam holding, the spade current holds spade S_0 down to a beam holding level. Since the series value of R_1 plus R_2 exceeds that of R''_s and the capacity which must be charged in the sum of a spade and a target's capacity, C_s plus C_T ; the RC time constant for spade S_0 is longer than that for spade S_3 , so a beam resetting action on spade S_0 is assured due to an adequate lower potential remaining on spade S_0 after the beam is cut off of target T_3 . The simultaneous occurrence of beam clearing and beam resetting, limited only in a slight manner by the time constant of resistor R_2 and spade capacity C_s in the lowering of the potential on spade S_0 , insures high speed and highly reliable operation.

The switches 45 and 46 of Fig. 3 provide the proper connections for stable beam holding and transfer when in one of their positions and for beam clearing and resetting when in the other position. From inspection, it can be seen that this requires a large number of double-pole, double-throw switches to provide a full range of variable counting. Fig. 5 shows a multi-position switch which provides the required reconnections for various counts which can be selected. One switch member 47 connects to the selected count's target, which in Fig. 5 is target T_4 for a count $n=4$. Bridging member 49 is disconnected from target T_4 and its associated resistor R_T . Another switch member 48 connects resistor R_3 to the resistor R_X for the particular spade 33 which is to be rendered unstable. Movement of the switch to various positions accomplishes the above reconnections for whatever position is selected. The resistors shown as R_X and R_3 could be lumped and placed in the circuit where the resistors R_X are shown. The important factor is that the ohmic value of R_s and R_X plus R_3 in parallel be equal to the resistance R''_s needed to make each particular position's spade unstable for beam holding after the preceding or j spade returns to voltage V_s . There is a variation of the ohmic value needed for R''_s depending on the position of the selected spade with respect to spade S_0 . This variation arises from the dependence of the transient spade characteristic 40, shown in Fig. 2, upon the voltage of the preceding spade. Whatever the count that is used, spade S_0 is the spade which is lowered in potential by the IR drop through R_2 caused by target current from the selected target. Spades which are more than two positions removed from spade S_0 quickly collapse from characteristic 40 to characteristic 41 because the preceding spade rises quickly in its potential when the beam advances from it. However,

spades within two positions of spade S_1 do not collapse their characteristic as rapidly, due to the proximity of spade S_0 which does not rise in potential. A lower value load resistance is required for spades near spade S_0 , to facilitate beam cut-off in those positions.

Fig. 6 shows a bi-directional counter. Only the odd numbered positions 1, 3, 5, 7 and 9 are provided with spade resistors R_1 and R_2 and target resistor R_T for stable beam holding. Even positions 0, 2, 4, 6 and 8 are unstable positions in that resistors R'' 's are too low in ohmic value to enable the associated spade to hold the beam stably, so the beam is cleared. Targets of even positions are connected to spade electrodes of odd positions to reset a new beam on the particular odd position to which a particular even target is connected. With multiple-pole, double-throw switch 50 connected as shown, switching pulses will advance the beam to the left in Fig. 6 which is clockwise in the circular configuration shown in Fig. 1.

Assume the beam is on target T_1 and the next switching pulse moves the beam to target T_2 . Spade S_2 is connected to a resistor R'' 's and accordingly is unstable for beam holding. Target T_2 connects to resistors R_1 and R_2 for spade S_3 . Target current lowers the potential of spade S_3 so the beam is reset to target T_3 . The practical sequence is a rapid beam switch from target T_1 to target T_3 when a switching pulse was applied. For this circuit, switching grids 35 are in a single common circuit and pulses of controlled short duration are applied to all grids simultaneously. With this connection of switching grids 35, the next pulse will switch the beam from target T_3 to T_4 to cutoff, while a reset of the beam to target T_5 occurs. In this manner the beam moves to positions 1, 3, 5, 7 and 9 in sequence.

With switch 50 thrown to the presently dotted position of Fig. 6, beam movement will be to the right or counter-clockwise in the circular configuration shown in Fig. 1. With the beam on target T_1 , the next switching pulse moves the beam to target T_2 and to cut-off as described. However, target T_2 connects to R_1 and R_2 for spade S_9 to where a beam is reset on target T_9 .

The next switching pulse moves the beam to target T_0 and cut-off, while target current from target T_0 lowers the potential of spade S_7 and causes a beam to reset on target T_7 . The sequence thus is 1, 9, 7, 5, 3, 1, etc., when switch 50 is connected to dotted position.

There is thus provided a variable counter providing for high speed and highly reliable operation at any count within the beam switching tube's maximum count capability, which can provide for bi-directional counting sequence.

What is claimed is:

1. A variable counter comprising a magnetron beam switching tube having a plurality of positions each including a beam forming and holding electrode, a switching grid and a target electrode, first resistance means for connecting said beam forming and holding electrodes to a voltage supply, second resistance means for connecting said target electrodes to a voltage supply, first circuit switching means connecting a selected target electrode to said first resistance means where connected to a particular beam forming and holding electrode, and second circuit switching means connecting a selected beam forming and holding electrode associated with said selected target electrode to said first resistance means to provide a lower resistance connection thereto than is provided by said first resistance means to all other beam forming and holding electrodes.

2. A variable counter comprising a magnetron beam switching tube having a cathode, a plurality of spade electrodes of switching grid electrodes and of target electrodes with said electrodes associated in groups of one of each type to provide beam holding positions therein, first resistance means having a plurality of

branches connected to said spade electrodes, second resistance means connected to said target electrodes, and a multiposition multipole connecting means having a first pole connected to said first resistance means where connected to a particular spade electrode and connectable to said target electrodes in single sequence, a circuit interrupting means disconnecting said target electrodes from said second resistance means in the same single sequence and a second pole connectable to branches of said first resistance means particular to each spade electrode in the same single sequence to provide a parallel path in said first resistance means.

3. A variable counter comprising a magnetron beam switching tube having a plurality of beam holding positions with each position including a spade electrode, a switching grid electrode and a target electrode functionally associated together, resistance means having a plurality of conductive paths and separately connected to said spade electrodes and to said target electrodes, first switching means connecting said target electrodes in single sequence to said resistance means where connected to a particular spade electrode, and second switching means connecting at least two conductive paths of said resistance means in parallel circuit to said spade electrodes in the same single sequence.

4. A variable counter as in claim 3, wherein said first switching means includes a disconnecting means to break in the same single sequence the separate connections of said target electrodes to said resistance means.

5. A variable counter comprising a magnetron beam switching tube having a plurality of electron beam holding positions each including an electron beam forming and holding electrode, a beam switching electrode, and a target electrode, a plurality of first resistors connected one to each of said beam forming and holding electrodes and adapted to be connected to a common voltage supply, a plurality of second resistors provided for connection one each in parallel with each of said first resistors and means for making and breaking said last named parallel connection, a plurality of third resistors connected to each of said target electrodes and adapted to be connected to a common voltage supply, means for connecting each of said target electrodes to by-pass its third resistor, means connected to one of said beam forming electrodes for automatically lowering the electrical potential thereon when electron flow to said target electrodes is interrupted, and switching means connected to the target electrodes at said odd-numbered positions for switching to different beam holding electrodes for directing an electron beam in one direction or in the opposite direction in said tube.

6. A variable counter comprising a magnetron beam switching tube having a plurality of odd and even-numbered electron beam holding positions with each position including a beam holding electrode, a beam switching electrode and a beam target electrode, a first resistance means connected to the beam holding electrodes of said even-numbered positions and having a low value which renders said electrodes unable to hold an electron beam in the even-numbered positions, second resistance means connected to each beam holding electrode of the odd-numbered positions and having sufficient resistance to render said electrodes capable of holding an electron beam in position, third resistance means connected to each of the target electrodes at an odd-numbered position and adapted to be coupled to a voltage supply, and switching means for connecting the target electrodes at even-numbered positions either to the resistance means associated with the next adjacent beam holding electrode ahead of it in one direction or to the resistance means connected to the holding electrode at the third position away from it in the opposite direction.

7. A variable counter comprising a magnetron beam switching tube having a plurality of odd and even-numbered

bered electron beam holding positions with each position including a beam holding electrode, a beam switching electrode and a beam target electrode, first resistance means connected to the beam holding electrodes of said even-numbered positions and having a low value which renders said electrodes unable to hold an electron beam in the even-numbered positions, second resistance means connected to each beam holding electrode of the odd-numbered positions and having sufficient resistance to render said electrodes capable of holding an electron beam in position, third resistance means connected to each of the target electrodes at an odd-numbered position and adapted to be coupled to a voltage supply, and switching means connected to said target electrodes at the odd-numbered positions for coupling said last-mentioned target electrodes to two different beam holding electrodes whereby an electron beam may be switched in different directions in said tube.

8. A variable counter comprising a multi-position electron beam tube having a plurality of beam holding positions with each position including a target electrode adapted to receive an electron beam, a spade electrode adapted to form and hold an electron beam on its associated target electrode, and a switching electrode adapted to switch an electron beam from one position to the next; a variable resistance means coupled to each spade electrode and having a range of resistance values such that each spade may be operated in both stable and unstable

conditions; each spade being able to hold an electron beam in the stable condition and unable to hold an electron beam in the unstable condition; and means coupled to each target electrode for selectively coupling any target electrode to a selected spade electrode so that an electron beam may thereby be reset from an unstable spade to said selected spade.

9. A variable counter comprising a multi-position electron beam tube having a plurality of beam holding positions with each position including a target electrode adapted to receive an electron beam, a spade electrode adapted to form and hold an electron beam on its associated target electrode, and a switching electrode adapted to switch an electron beam from one position to the next; 10 a resistance means connected to each spade electrode and of sufficient magnitude to render each spade stable in operation; means adapted to be coupled to each spade to render each spade unstable in operation and unable to form and hold an electron beam; and means coupled to 15 each target electrode for selectively coupling any target electrode to a selected spade electrode so that an electron beam may thereby be reset from an unstable spade to said selected spade.
